UNITED STATES PATENT OFFICE

172,767

VASE OR THE LIKE

Gerald John Rotterdam, Toledo, Ohio

Application March 16, 1953, Serial No. 24,031

Term of patent 14 years

(Cl. D29—28)

To all whom it may concern:

Be it known that I, Gerald John Rotterdam, a citizen of the United States of America, residing at Toledo, Lucas County, Ohio, have invented a new, original, and ornamental Design for a Vase or the Like, of which the following is a specification, reference being had to the accompanying drawings:

Fig. 1 is a front elevational view of a vase or the like showing my new design;

Fig. 2 is a side elevational view thereof taken from the left of Fig. 1 and drawn to a smaller scale;

Fig. 3 is a side elevational view thereof taken from the right of Fig. 1 and drawn to a smaller scale; and

Fig. 4 is a rear elevational view thereof drawn to a smaller scale.

I claim:

The ornamental design for a vase or the like, as shown.
